BITUMEN SPREADER

Filed Aug. 28, 1926

Charles G. Talbott, INVENTOR

BY

Daniel J. Mayne, ATTORNEY

UNITED STATES PATENT OFFICE

CHARLES G. TALBOTT, OF STAMFORD, CONNECTICUT, ASSIGNOR TO THE BARRETT COMPANY, A CORPORATION OF NEW JERSEY

BITUMEN SPREADER

Application filed August 28, 1926. Serial No. 132,068.

This invention relates to bitumen spreaders and relates more particularly to a portable device for spreading pitch or other bitumen in the laying of roofing felt and to the 5 method by which said device may be operated.

When building large roofs such as those used upon apartment houses, factory buildings, etc., it has been the practice to place a 10 plurality of layers of saturated felt upon the roof structure, coating each layer with pitch or asphalt before the succeeding layer of felt is applied and to then coat the top ply of felt with a thick layer of bitumen such as pitch 15 or asphalt. Heretofore this has been done by hand, the bitumen being heated in tanks upon the ground and hauled to the roof in buckets where it is utilized, the bitumen being spread upon the roof by the use of 20 squeegees and mops. Needless to say, this involves considerable labor and numerous difficulties are encountered such as the bitumen "freezing" before it is completely spread.

I am aware, of course, that bitumen has 25 been heated in tanks heretofore and that provision has been made to move such tanks across the surface that is to be coated, for instance such as is practiced in road building work wherein the material is sprayed onto 30 the road surface from a tank mounted upon a truck. I am also aware that provision has been made to "by-pass" a portion of the material back into the tank, such "by-pass", however, being provided at a point relatively 35 adjacent to the tank and not being provided for the purpose contemplated by my invention.

My invention includes a portable tank, adapted to be heated, mounted upon trucks 40 upon which may also be placed a small engine and pump. The pump forces the bitumen, which may be heated in the tank, thru a long flexible hose to a spreading nozzle, from which a certain amount of the bitumen is re- 45 turned to the tank in order to maintain the flow of the material to the spreading nozzle as will be more fully hereinafter described.

It is among the objects of my invention, therefore, to provide a relatively portable 50 tank and a spreading nozzle connected there-

to by means of a long flexible hose whereby bitumen may be efficiently spread upon all parts of a roof which is being constructed. It is a further object of my invention to provide for the continuous circulation of the bitumen from the tank to the spreading nozzle and back to the tank and also to provide means for "blowing out" the nozzle and the lines connecting it with the tank.

Further objects and the specific nature of 60 my invention will be more fully understood from the following description and the appended drawing made a part hereof.

In the drawing, in which like reference characters refer to like parts— 65

Fig. 1 is a side elevation, partly in section, 65 of my improved pitch spreading device.

Fig. 2 is a section thereof taken along the line 2—2 of Fig. 1, the insulation, wheels and truck not being shown. 70

Fig. 3 is a plan view of the spreading nozzle assembly and

Fig. 4 is a section of the intake pipe assembly, represented by a section taken along the line 4—4 of Fig. 1. 75

The reference character 1 designates generally the tank which I propose to employ. Insulation 2 may be provided to increase the thermal efficiency of the tank and a manhole 3 may be employed in the top of the tank for 80 purposes of inspection, cleaning, etc. A large portion of the weight of the tank is carried by wheels 4 secured in any convenient manner to the side of the tank near the center thereof. A truck or frame work for the tank and engine is also provided, the weight thereof being carried by the wheels 4 as well as a small wheel 5. A handle 6 may be provided for manipulating the tank into position. 85

Upon the front end of the truck is mounted a small gas engine 7, or other means of power for pumping and a fuel tank 8 for supplying fuel thereto. A rotary pump 9 of any well known construction is connected to the engine. It is by means of this pump that 90 the molten bitumen, for instance pitch, may be circulated thru the system, as will herein-after be more fully described.

In the lower portion of the tank, and occupying approximately three-quarters of the 100

length thereof, is located a fire box 11 having two compartments 12 and 13 formed by a baffle wall 14. Any convenient method of heating may be employed, altho I have found 5 a small oil burner to be most satisfactory.

At a convenient location in the front end of the tank is located a hole 16 and upon either side thereof a plate 17 and 18, riveted or otherwise secured to the tank. Into the plate 17 10 is threaded a pipe 19 which leads to the pump. Within the plate 18 is swiveled a pipe 21 having a lower open ended portion 22 which, during normal operation, is positioned near the bottom of the tank 1 and parallel there- 15 to. A chain 23 is fastened at one end to the portion 22 of the pipe 21 and at the other end to the inside of the manhole 3 for a purpose to be hereinafter more fully described.

As the molten pitch is pumped from the 20 tank 1 thru the pump 9, it passes into the pipe 25 and thence into a long flexible metal hose 26, from which it is conducted into the pipe 27, which communicates with one end of the spreading nozzle 28. The pitch may then pass 25 thru the nozzle 28 and out the other end thereof thru the pipe 29 secured thereto and into another flexible metal hose 30 thru the pipe 31 and back into the tank 1. The pipe 31 is secured to the tank by a suitable flange 30 32. The spreading nozzle 28 is provided with a lipped opening 33 which is controlled by a rotary slide valve 34, which, in turn, may be manipulated by the handle 35.

Operation of the device is as follows:

The tank and its accompanying assembly 35 is hoisted to the roof where it is desired to apply pitch, the tank 1 being filled with pitch thru the manhole 3. Fire is started and maintained in the fire box 11 to bring the pitch to and 40 maintain it at the proper fluidity. The end 22 of the swivel pipe 21 may, by means of the chain 23, be drawn entirely out of the pitch and the engine 7 and pump 9 started. The opening 33 of the nozzle 28 being closed, the 45 pipe 22 is allowed to drop into the pitch which immediately commences its circulation thru the spreading nozzle 28. The tank 1 being in the approximate location in which it is desired to work, the spreading nozzle 28 may 50 then be manipulated as desired, so that pitch may be spread over a considerable portion of the roof, remote from the tank 1, without moving said tank. The flexible lines 26 and 30 may be approximately 25 ft. or more in 55 length so that a workman can manipulate the spreading nozzle 28 over the roof as desired. By means of the lever 35 the spreading nozzle 28 is caused to deliver an even sheet of pitch to the felt which has previously been applied 60 to the roof structure.

The flow of pitch to the nozzle 28 is such 65 that a certain portion thereof will continually circulate to and thru the nozzle and back to the tank, even though the opening 33 be opened to a maximum. When the opening

33 in the nozzle is closed this recirculation of pitch is, of course, increased because of the fact that all the pitch pumped from the tank must return thereto. Thus it will be readily seen that the entire spreading assembly 25 to 70 31 is at all times kept at approximately the same temperature as the tank 1 so that "freezing" of any of the lines does not occur. When the job is completed or it is desired to discontinue work for any length of time the pipe 22 may be raised by means of the chain 23 so that air will be admitted to the pumping system. The pitch in the lines and in the nozzle 28 will thereby be "blown out" so that same will be clean when it is desired to resume operation. 80

By the use of my invention the cost of spreading pitch upon a roof may be very materially decreased, tedious hand spreading methods being thereby dispensed with. 85

In the claims where the term "bitumen" is referred to it is intended to include pitch, asphalt and all other types of materials which could be heated and spread upon a roof in the manner and for the purpose which I 90 have disclosed. Obviously, the material to be handled is immaterial when considering the broad aspects of my invention.

I claim:

1. In combination a tank, means for heating bitumen therein, a pump for withdrawing bitumen from said tank, a mobile spreading nozzle, a flexible line establishing fluid communication between the outlet of said pump and one end of said nozzle, a flexible return line establishing communication between the other end of said nozzle and the tank and means for blowing out said lines. 100

2. In combination a tank, means for heating bitumen therein, a pump for withdrawing bitumen from said tank, a mobile spreading nozzle, a flexible line establishing fluid communication between the outlet of said pump and one end of said nozzle, a flexible return line establishing communication between the other end of said nozzle and the tank and means operable to control both the flow of bitumen and the blowing out of said lines. 110

3. An apparatus for applying bitumen comprising in combination a tank for containing bitumen, heating means associated with the tank, a pump, means for operating the pump, a nozzle for spreading bitumen, a line connecting said pump and said nozzle, a return line connecting said nozzle and said tank, a pipe connected to said pump and having an open end movable within the tank, and means for regulating the position of the open end of said pipe. 115

In testimony whereof I affix my signature.
CHARLES G. TALBOTT.
